UNITED STATES PATENT OFFICE.

EDWARD F. WESTON, OF NEWARK, NEW JERSEY, ASSIGNOR TO WESTON ELECTRICAL INSTRUMENT CORPORATION, OF NEWARK, NEW JERSEY, A CORPORATION OF NEW JERSEY.

DESIGN FOR A CASE FOR ELECTRICAL INSTRUMENTS.

Application filed July 29, 1927. Serial No. 22,953. Term of patent 14 years.

To all whom it may concern:

Be it known that I, EDWARD F. WESTON, a citizen of the United States, residing at Newark, in the county of Essex, and State of New Jersey, have invented a new, original, and ornamental Design for a Case for Electrical Instruments, of which the following is a specification, reference being had to the accompanying drawing, forming part thereof, and wherein—

Fig. 1 is a front view of the case, and
Fig. 2 is a central vertical section of the case.

I claim:

The ornamental design for a case for electrical instruments, as shown.

EDWARD F. WESTON.
